UNITED STATES PATENT OFFICE.

WILLIAM T. CARROLL, EDGAR J. CARROLL, AND ELBERT H. CARROLL, OF WORCESTER, MASSACHUSETTS.

TOP ROLL FOR SPINNING-MACHINES, &c.

SPECIFICATION forming part of Letters Patent No. 320,333, dated June 16, 1885.

Application filed July 29, 1884. (No model.)

To all whom it may concern:

Be it known that we, WILLIAM T. CARROLL, EDGAR J. CARROLL, and ELBERT H. CARROLL, citizens of the United States, and residing at 5 Worcester, in the county of Worcester and State of Massachusetts, have invented certain new and useful Improvements in Top Rolls for Spinning-Machines, &c.; and we do hereby declare that the following is a full, clear, and 10 exact description of the invention, which will enable others skilled in the art to which it appertains to make and use the same, reference being had to the accompanying drawings, which form a part of this specification, 15 and in which—

Figure 1 is a vertical sectional view of our improved roller for drawing-frames. Fig. 2 is a perspective view of the same, showing one of the shells removed and shown beside the shaft. 20 Fig. 3 is a view of one of the hollow oil-conducting bearing-pins. Fig. 4 is a view of one of the anti-friction shells. Fig. 5 is a perspective view of a slight modification of the invention, showing one shell removed from the shaft; 25 and Fig. 6 is a longitudinal section of one end of the same.

Similar letters of reference indicate corresponding parts in all the figures.

Our invention has relation to the weighted 30 leather-covered rollers used in a drawing-frame or similar machinery, together with fluted rollers for drawing slivers; and it consists in the improved construction and combination of parts of the shafts, bearings, and 35 rollers, as hereinafter more fully described and claimed.

In the accompanying drawings, the letter A indicates the shaft, the ends of which are hollow, as shown at B, for the reception of the 40 reduced inner ends, C, of the bearing-pins D, which have square or flattened heads E, which are secured in the support for the rollers movable vertically in any suitable manner, and a duct or channel, F, opening in the inner end 45 of the pin and in the upwardly-facing side of the head adapted to conduct oil or similar lubricant into the hollow ends of the shaft. The middle portion, G, of the shaft is adapted to 50 revolve in a suitable bearing in the weighted or spring-actuated saddle, which holds the roller down against the fluted rollers, and the ends

H of the shaft are reduced and have wide annular recesses I, in which anti-friction shells or tubes J are placed, turning freely upon the reduced portion of the shaft and being flush 55 with the shoulders at the ends of the recesses at their ends, and increasing in thickness toward their middles, so as to offer a curved surface. The shaft has perforations K at its ends, passing from the hollow chambers formed 60 in the said ends and opening in the annular recesses upon the ends of the shaft, and the anti-friction tubes or shells have perforations L, registering with the perforations in the shaft, thus allowing the lubricant to flow from 65 the interior of the ends of the shaft between the annularly-recessed portions of the shaft and the anti-friction shells and over the latter. The tubular shells M, which have preferably a leather-covering, M', are journaled upon the 70 ends of the shaft, turning upon the anti-friction shells; and it will be seen that the anti-friction shells, being thicker at their middles than at their ends, the leather-covered shells will be enabled to adapt themselves to any inequalities of the stock passing under them and to find themselves a bearing.

In Fig. 5 is shown a slight modification of the shaft, which dispenses with the annularly-recessed ends and anti-friction shells, and has 80 its ends reduced and formed slightly bulging toward the middle, and provided with spiral channels N, which serve to conduct the lubricant from the perforations in the shaft, through which it passes out over the entire surface 85 of the reduced end. The bearing-pins are also shown provided with screw-threaded ends, which fit into the female-threaded ends of the recesses in the ends of the shaft, thus rendering the shaft rigid while the shells revolve.

Having thus described our invention, we claim and desire to secure by Letters Patent of the United States—

1. The combination of a shaft, having its 95 ends provided with recesses or bores and with perforations opening from the said bores in the sides of the shaft, bearing-pins having their ends fitting in the bores of the shaft, provided with an enlarged flattened head and 100 with a channel opening in the upper side of the said head and in the end of the pin, and

a shell or tubular roller journaled upon the end of the shaft, as and for the purpose shown and set forth.

2. The combination of the shaft having the reduced ends provided with the annular recesses, the anti-friction shells fitting and turning in the said recesses and having their middles thicker than their ends, and the shells or tubular rollers, as and for the purpose shown and set forth.

3. The combination of the shaft, having its ends provided with longitudinal bores having openings through the sides of the ends and having the wide annular recesses, the anti-friction shells increasing in thickness at their

middles and having perforations, the shells or tubular rollers, and the bearing-pins having the enlarged flattened heads, the reduced ends, and the channel opening at the end and in the upper side of the enlarged heads, as and for the purpose shown and set forth.

In testimony that we claim the foregoing as our own we have hereunto affixed our signatures in presence of two witnesses.

WILLIAM T. CARROLL.

EDGAR J. CARROLL.

ELBERT H. CARROLL.
